UNITED STATES PATENT OFFICE

1,928,935

ADVERTISING DISPLAY DEVICE

Wilfred M. Harding, North Canton, Ohio, assignor to The Hoover Company, North Canton, Ohio, a corporation of Ohio

Application October 22, 1931. Serial No. 570,280

6 Claims. (Cl. 35—12)

The present invention relates to advertising display devices in general and particularly to an advertising display device in which the suction power of a suction cleaner is evidenced. More specifically the present invention comprises the provision, in an advertising display device, of a construction in which means are provided to simultaneously lift and weigh a human being by means of suction created by a suction cleaner driven by electricity.

It is an object of the present invention to provide a new and improved advertising display device for a suction cleaner. A still further object is the provision, in an advertising display device, of a construction in which a human being is lifted by the suction created by a suction cleaner, means being provided to weigh the person lifted. These and other more specific objects will appear upon reading the following specification and claims and upon considering in connection therewith the attached drawing to which they relate.

Referring now to the drawing, which a preferred embodiment of the present invention is disclosed.

25 In Figure 1 is disclosed a front view of the advertising display device comprising the present invention.

Figure 2 is a partial section looking in the direction of the arrows upon line 2—2 in Figure 1.

30 Figure 3 is a section of the suction-actuated collapsible chamber in a partially collapsed condition.

Referring again to the drawing a framework is disclosed which comprises a tripod having three spaced legs, 10, 10, 10. Legs 10, 10, 10 are connected in rigid relationship by means of a triangular frame comprising cross members 11, 11, 11, the legs 10 of the frame extending above the cross members. The upper ends of the legs 10, 10, 10 are bent so as to extend substantially horizontally and are connected, by means of bolts 12, 12 etc. to a collapsible chamber which is indicated generally by the reference character 13 and which comprises an upper rigid side 14, to which the bolts 12, 12 are connected, a rigid movable side 15, and a collapsible enclosing side 16 between sides 14 and 15 which may be formed of suitable substantially air proof material and which is itself provided with reinforcing circular rods 17, 17.

Suspended from the movable rigid side 15 of the chamber 13, is a scale 18 which supports, through a suitable framework 19, a chair 20, the relationship between the parts being such that with the chamber 13 in the expanded position or

relationship the chair 20 is just resting upon the supporting surface, and the scale 18 indicates a zero reading.

Positioned at the side of the triangular framework, and preferably in front of the chair 20, is a suction cleaner which is indicated generally by the reference character 21. This cleaner is of a well known type and is connected, by means of an electric conduit 22, to a source of electric power in order that the machine may be driven to create a suction. Extending between the cleaner 21 and the chamber 13 is a flexible conduit 23 which, at its cleaner end is connected to the suction inlet of the machine and, at its chamber end, is connected in sealed relationship with the interior of the chamber 13 through the rigid wall 14. Enclosing the upper end of the chamber-supporting frame is a suitably formed vertical wall which is indicated by the reference character 24. Wall 24 is provided on its forward face, or that viewed when facing the scale and chair, with suitable instructions as to the purpose of the mechanism or display device. This wall also performs the useful function of covering and hiding from the observers the comparatively unsightly chamber which is positioned therewith.

In the operation of a display device constructed in accordance with the present invention the chamber supporting frame is positioned in a preferably open space where it can be readily observed. The suction cleaner is connected, by means of its electric cord 22, to a source of power and is positioned preferably in front of the chair 20 in order that the occupier thereof must, of necessity, be aware of its presence. The operator of the display device turns on the electric cleaner motor thereby causing a reduced pressure to be created therein which functions to draw air through the hose 23 and from the chamber 13. The party to be weighed sits in the chair 20 in an ordinary manner and, as the air within the chamber 13 is withdrawn, the movable side 15 thereof is lifted upwardly or, more accurately, is forced upwardly by the greater exterior pressure. As the movable side 15 moves upwardly the reading upon the scale 18 increases until the correct weight of the occupant of the chair is indicated at which time the chair will be lifted, together with its occupant, from the supporting surface and he will, of necessity, become aware of the fact, as will all observers, that the suction cleaner, which is operating before him, has lifted him from the floor. To return the device to initial position it is only necessary to disconnect the

suction cleaner from its source of electric power whereupon it will no longer create a suction; exterior air at atmospheric pressure will rush through the hose 23 to relieve the reduced pressure area within the chamber 13 thereby permitting that member to return to its extended position, shown in Figure 2, and the chair will again rest upon the supporting surface at which time the occupant may properly make his exit. The device is educational in that it evidences to the observer in an impressive manner the suction power of the suction cleaner which is before him and which makes possible his being weighed and his being lifted from the supporting surface.

15 I claim:

1. In an advertising display device, a collapsible chamber having a rigid movable side, means supporting said chamber above a supporting surface, a seat suspended from the movable side of said chamber, and a suction-creating device comprising a suction cleaner positioned near said seat connected to and adapted to collapse said chamber for the purpose of lifting said seat in order to show the suction power of said cleaner.

2. In an advertising display device, a collapsible chamber having a rigid movable side, means supporting said chamber above a supporting surface, a scale suspended from the movable side of said chamber, a seat suspended from said scale, and means to collapse said chamber to lift said scale and said seat.

3. In an advertising display device, a collapsible chamber having a rigid movable side, means supporting said chamber above a supporting surface, a scale suspended from the movable side of said

chamber, a seat suspended from said scale, and means to collapse said chamber to lift said scale and said seat comprising a suction cleaner.

4. In an advertising display device, a collapsible chamber having a rigid movable side, means supporting said chamber above a supporting surface, a scale suspended from the movable side of said chamber, a seat suspended from said scale and touching the supporting surface with the chamber in the expanded position, and a suction cleaner connected to said chamber adapted to draw air therefrom to collapse said chamber to lift said scale and chair.

5. In an advertising display device, expandable and contractible means interiorly sealed from the atmosphere, visible object-carrying means supported by a movable part of said first mentioned means, and a visible suction cleaner connected to said first mentioned means to exhaust air therefrom to lift said object-carrying means for the purpose of illustrating the suction power of said suction cleaner.

6. In an advertising display device, expandable and contractible means interiorly sealed from the atmosphere, a support holding said means above a supporting surface, a visible scale carried by a movable part of said means, a visible chair carried by said scale and positioned within the confines of said support, a visible suction cleaner adapted to create a reduced pressure, and means connecting said expandable and contractible means to a low pressure point of said suction cleaner.
